UNITED STATES PATENT OFFICE.

ISAAC S. CORSON, OF GREAT FALLS, MONTANA.

WEED BURNER.

Application filed September 7, 1922. Serial No. 586,698.

To all whom it may concern:

Be it known that I, ISAAC S. CORSON, a citizen of the United States, residing at Great Falls, in the county of Cascade and State of Montana, have invented new and useful Improvements in Weed Burners, of which the following is a specification.

This invention relates to weed burners and is an improvement over my basic Patent No. 1,410,659, issued March 28, 1922. The primary object of my invention is to provide a simple and economic weed burner which will effectively destroy all forms of plant and animal life adjacent the surface of the soil which might be deleterious to proper cultivation. In accomplishing the above object, a simplified oil burner system is provided, tractive means comprising castors and means for raising and lowering the body frame are incorporated, means for mashing down and chopping up the weeds and extinguishing the fire are included together with various other improvements.

With the above and other objects in view which will appear as the description proceeds, the invention consists of the novel construction, adaptation, arrangement and combination of parts hereinafter described and claimed.

These objects are accomplished by devices illustrated in the accompanying drawings, wherein—

Figure 1 is a top plan view of a weed burner embodying the features of my invention;

Fig. 2 is a view in side elevation of same; Fig. 3 is a view in longitudinal vertical section taken substantially on a broken line 3, 3 of Fig. 1;

Fig. 4 is a view in transverse vertical section taken on a broken line 4, 4 of Fig. 1;

Fig. 5 is a fragmentary detail view, partly in vertical section, showing the disc roller mountings and associated parts; and

Fig. 6 is a fragmentary view partly in vertical section showing the means for raising and lowering the body frame.

Referring to the drawings, throughout which like reference numerals designate like parts, the numerals 5 and 6 designate the side walls of the supporting body frame which are held in spaced apart relation at their upper edge portions by transverse L shaped beams 8, 9, 10 and 11. The forward ends of said side walls are cut away and their outer end portions are bent inwardly

where they are bolted, as at 12, to an angular spanner member 13. A looped clevis 14 is centrally secured to said spanner member for attaching the propelling means. 60

Plates 15 are bolted to the forward end portions of said side walls and curved outwardly at their middle portions to form rounded vertical apertures 16. Standards 17 of castors 18 are revolvably seated within 65 said apertures and serve together as bearings for the forward end of the supporting body frame. Plates 19 are secured to the reduced end portions and are similarly curved to form rounded vertical apertures 70 20 wherein standards 21 of castors 22 are seated and serve as bearings for the rear end of said supporting body.

The means for lowering and raising the supporting body frame comprises caps 23 75 adapted to revolvably seat on top of the standards 17 and 21 having adjustable screws 24 through the lower end portions thereof adapted to fit in annular grooves 25. Sleeves 26 are formed on the upper end 80

portions of said caps which serve as bearings for transverse windlass rods 27 having square ends 28 projecting outside of said sleeves. Cables 29 having their upper ends secured within holes 30 and their lower ends 85

secured to the transverse beams 8 and 11, are adapted to be wound around said windlass rods by turning same with detachable handles 31 applied to the square ends 28. Lug brackets 32 are secured to the side walls 90

5 and 6 and serve as stops for said handles to prevent same from turning backwards. It will now be apparent that the entire supporting body may be raised or lowered on said standards to suit the nature of the 95 soil and other surface conditions.

For the purpose of mashing down weeds, stalks and stubble, I have provided a shaft 33 extending transversely adjacent the lower forward end portions of the side walls 5 100 and 6 with traction rollers 34 and 35 fixedly mounted thereon adjacent the inner sides of said walls. A plurality of rollers 36 are rotatively mounted on said shaft between said traction rollers with sufficient 105 space therebetween to permit independent rotary motion necessary in turning corners. The outer end portions of said shaft projecting exteriorly of said walls are secured in bearings 37 and 38 formed on the lower 110 ends of depending arms 39 and 40. The arm 39 is pivotally secured at its upper end

to a short crank shaft 41, more fully hereinafter described, and the arm 40 is pivotally secured at its upper end to a stub shaft 42 mounted in a bearing on the upper flanged portion of the side wall 6. Said arms are of equal length and slots 43 are provided in said side walls concentric with said crank and stub shafts so that when the rollers 36 pass over an obstruction they will 5 be lifted as said arms swing upwardly about their pivotal bearings carrying the shaft 33 within said slots. 10

A shaft 44 is mounted in bearings through the side walls 5 and 6 adjacent the lower 15 and rear end portions thereof and traction rollers 45 are fixedly secured thereto adjacent the inner sides of said walls. A plurality of disc rollers 46 are rotatively mounted on said shaft between said traction rollers 20 with sufficient space therebetween to permit independent rotary motion necessary in turning corners. A sprocket wheel 47 is secured to the end of said shaft exteriorly of the wall 5 and a sprocket chain 48 leads 25 upwardly to a corresponding sprocket wheel 49 fixedly secured to the outer end of a roller shaft 50 mounted in bearings on the upper flanged portion of said side walls. A hopper 51 is superimposed on the body 30 frame and is detachably secured thereon by an angle bracket 52. Referring to Figs. 2 and 3 it will be seen that fertilizer, grain or other material may be automatically fed from said hopper by the rotary motion communicated to said roller when the device 35 is drawn over the ground.

A sprocket wheel 53 is secured to the outer end of the shaft 33, exterior to the wall 5, from which a sprocket chain 54 leads upwardly to a similar sprocket wheel 55 secured to the crank shaft 41. Said crank shaft is mounted in bearings on the upper side of the body supporting frame and is provided with a clutch 56 by means of which 40 it may be thrown into or out of action. The crank portion of said shaft is connected to the plunger of a pump 57 and it will be obvious that as the device is drawn over the ground motion will be communicated to said 45 pump whereby air may be forced upwardly through the pipe 58 and into the upper portion of a fuel tank 59 above the liquid fuel contained therein.

The cylindrical tank 59 rests in supports 55 60 and is secured thereon by straps 61 fastened to the transverse beams 10 and 11. An opening for filling said tank is centrally provided in the upper side thereof and a screw cap 62 is arranged to cover same to prevent the escape of air under pressure. A gage 63 is provided to indicate the pressure 60 within said tank and a safety valve 64 is provided for limiting said pressure.

The pressure within the tank 59 forces the 65 liquid fuel through a centrally located sup-

ply pipe 65, having a cut off valve 66 therein, and distributes same through a plurality of T connections 67, having regulator valves 68 thereon, to a double set of depending branch feeder pipes 69 and 70. Said T connections are supported by a central longitudinal plate 71 horizontally secured to the beams 9 and 10, and a vertical partition 72, projecting downwardly from said plate and secured at its upper edge portion to the underside thereof by angle brackets 73 and 74, divides the body portion of the vehicle 75 into two compartments 75 and 76. 70

The feeder pipes 69 and 70, projecting downwardly adjacent the partition 72 into the compartments 75 and 76 respectively, are bent to form horizontal portions 77 and 78 extending across the lower portions of said compartments close to the side walls 5 and 6 where they are again bent spirally 85 back upon themselves to form a plurality of gas generator coils 79 and 80 which end in closure caps 81 and 82. Said coils are respectively supported by brackets 83 secured to said side walls and central partition and the liquid fuel is thoroughly gasified by this arrangement before it reaches the discharge perforations in the lower portions of said coils where it is ignited as is well understood. 90

The compartments 75 and 76 are provided at their forward ends with an adjustable wind shield 84 hingedly secured to the beam 10 and at their rear ends with a corresponding wind shield 86 secured to the beam 9. Each 100 of the generator coils 79 and 80 is provided with fenders 88 secured at their ends to the side walls 5 and 6 and partition 72 and arranged transversely of said compartments slightly forward of said coils to protect 105 same from damage by any passing obstruction and also to strengthen the body frame.

In order to provide adequate draft for the burner elements, hoods are superimposed on the body frame over the compartments 75 and 76 comprising complementary halves 89 and 90 which are provided at their lower portions with horizontal flanges 91 and 92 adapted to seat on said body frame, and at their upper portions with vertical flanges 110 93 and 94 which are secured in spaced apart relation by spreader bolts 95, thus forming vents 96 and 97 through which the fumes are permitted to escape. 115

It will be evident that other compartments 120 may be laterally added to the device by simple alterations, and that same may be reduced to a single compartment if so desired. A seat, not shown, is ordinarily provided for the operator, and the device is drawn over 125 the ground by animal or automotive power either by itself or in tandem with a plough, harrow or other agricultural implements. The rollers 36 mash the weeds down so that the flames from the oil burner will strike 130

their roots. It will be understood that the fuel pressure is regulated to project flames sufficient to destroy all insects and germinant properties of deleterious vegetation and also 5 that the device is drawn over the ground at a speed regulated to prevent said flames from having any harmful effects on the life of the soil. The discs 46 serve to extinguish the fire and also to chop up the stalks of 10 charred weeds and other growth which is afterwards ploughed under thus adding to the fertility of the soil.

From the foregoing description taken in connection with the accompanying drawings, 15 the form of construction and method of operation of my weed burner will be readily apparent to those skilled in the art to which the invention relates, it being understood that the apparatus shown is 20 intended for illustration and that such changes may be resorted to as are within the scope and spirit of the invention.

Having thus described my invention what I claim and desire to secure by Letters 25 Patent is:—

1. The herein - described weed burner comprising a body having side walls arranged to serve as a draft chamber, weed burning means supported at the lower por-

tion of said walls, and a plurality of discs 30 rotatively mounted on a shaft within said walls for extinguishing the flames when said weed burner is moved over the ground substantially as specified.

2. The herein - described weed burner 35 comprising a body having side walls arranged to serve as a draft chamber, weed burning means supported at the lower portion of said walls, a plurality of roller members mounted on a shaft within said walls 40 for mashing the weeds and pivotal means whereby said rollers and shaft may swingingly pass over an obstruction substantially as specified.

3. The herein - described weed burner 45 comprising a body having side walls arranged to serve as a draft chamber, weed burning means supported at the lower portion of said walls, a plurality of roller members mounted on a shaft within said walls 50 for mashing the weeds, pivotal means whereby said rollers and shaft may swingingly pass over an obstruction, and a plurality of disc members mounted on a shaft within said walls for extinguishing the flames when said 55 weed burner is moved over the ground substantially as specified.

ISAAC S. CORSON.
